ELECTRICAL PRECIPITATOR

Charles Wasserman, Baltimore, Md., assignor to Koppers Company, Inc., a corporation of Delaware

Application December 7, 1953, Serial No. 396,616

16 Claims. (Cl. 183—7)

The present invention relates to voltage-regulating apparatus for electrical load devices and more particularly to a voltage-regulating apparatus designed for use with electrical precipitators.

In the operation of electrical precipitators, it has been found that the most efficient performance is obtained when the voltage between the electrodes of the precipitator is maintained at a value substantially higher than that at which sparks start to jump between the electrodes. In order to accomplish this, voltage regulating apparatus has been designed whereby precipitating voltage is raised and lowered, as necessary to maintain the rate of sparking or flashing within prescribed limits. In so designing this apparatus, it has been found necessary to provide circuits which delay downward adjustment of the voltage regulator, so that the voltage supply to the precipitator will not be undesirably corrected by any stray or minor sparking in the precipitator, which does not effect optimum performance. Such a predetermined delay has a tendency to permit the precipitator to operate under sparking conditions which do effect optimum performance during at least a portion of the period of delay. Moreover, mechanical devices which are readily subject to wear and are difficult to maintain in effective operation, have been used as part of a complex arrangement in order to obtain the desired result.

The present invention avoids these aforementioned disadvantages, providing a completely electrical circuit that permits instantaneous downward voltage adjustment responsive to only that sparking which effects optimum precipitator performance.

One of the features of the present invention is to provide to the primary of a high voltage rectifier transformer of an electrical precipitator a continuously rising voltage, having a preset rate of rise, which is instantaneously reduced a preset amount when a voltage value is reached causing undesirable current surge.

Still another feature of the present invention is to provide a voltage regulator wherein the rate of rise of voltage by the regulator and the magnitude of voltage reduction per surge directly determines the surging rate.

Another feature of the present invention is to provide a voltage regulator that automatically selects an optimum voltage range for a particular gas-dust condition of an electrical precipitator by automatically controlling the upper and lower voltage limits across the primary of the precipitator transformer maintaining a preset surging rate in the precipitator.

Another feature of the present invention is to provide a surge detector for an electrical precipitator which can operate either on positive half wave, negative half wave or the full wave, depending on the application of the high voltage rectifier to the precipitator.

Another feature of the present invention is to provide an amplifying system that permits voltage regulation of a supply circuit over a comparatively wide range.

Another feature of the present invention is to provide a voltage regulating circuit that eliminates expensive

2

variable transformers which are controlled by mechanical means tending to reduce the operating efficiency of the circuit.

More particularly, the present invention provides a voltage regulating apparatus for the main supply line of an electric load device comprising: a variable induction means positioned in the supply line; a sensing means positioned in the supply line for obtaining discrete responses to surges in the line created by raised voltage across the line; and a control means connecting the sensing means and the induction means, the control means causing the voltage in the main supply line to gradually rise through the induction means over a preset voltage range and to drop instantaneously a preselected amount in accordance with sensed responses in the line translated to the control means by the sensing means.

It will be obvious to one skilled in the art that various changes can be made in the arrangement, form, and type of the various elements disclosed without departing from the scope or spirit of the present invention.

Figure 1 of the drawings is a diagrammatic view of a circuit in accordance with the present invention for energizing an electrical precipitator.

Figure 2 of the drawings is a diagrammatic view of a portion of the circuit illustrating a modification which permits half wave operation.

Referring to Fig. 1 of the drawings, the automatic regulator is illustrated as being applied to the control of an electrical precipitator which is diagrammatically represented as comprising an extended surface collecting electrode 20, in the form of a vertically disposed, grounded, metallic tube and a wire discharge electrode 22 depending axially into the tube. Gas, bearing suspended particles of material, is passed through the tube 20 wherein the suspended particles are charged through discharge electrode 22 and deposited principally on the inner surface of the tube 20 from which the collected material is removed at selected intervals by rapping. It is to be understood that other type precipitators known in the art can be used in combination with the automatic regulator hereinafter disclosed.

The discharge electrode 22 of the disclosed precipitator is energized through a rectifier 24 which can be one of several types. For example, a mechanical, selenium or vacuum tube type rectifier can be used. The rectifier 24 is connected to the high voltage secondary winding 26 of a step-up transformer 28. The primary winding 30 of this precipitator transformer 28 is energized from a single-phase supply line L₁—L₂ of the main supply circuit through resistor M-4 and the adjustable resistance unit 32, both of which units are connected in series with the lines L₁—L₂. It is to be noted that the use of resistor M-4 is particularly advantageous when the regulator is used in conjunction with mechanical high voltage rectifiers, and is not necessarily required when the regulator is used with electronic type rectifiers. Paralleling the resistor M-4 is the alternating current winding 1—2 of the saturable reactor M-3. Also connected in series with the supply line L₁—L₂ is the current transformer T-3.

For the purposes of a clearer understanding, the automatic supply regulator can be considered as made up of three parts: an amplifying circuit I, a sensing circuit II, and a control circuit III. These circuits are respectively indicated on Figure 1 of the drawings by the broken line enclosures.

The amplifying circuit I, comprising a self-saturating magnetic amplifier M-1, which includes associated winding 9—10 and 11—12 and the rectifiers SM, when energized through a supply circuit 17—18, supplies maximum rated direct current through the direct current winding 3—4 of the saturable reactor M-3 in series with

the supply line L_1-L_2 of the main supply circuit. A direct current source $a-b$ is connected through an adjustable resistor $R-18$ with proper polarity to bias winding $7-8$ of the magnetic amplifier $M-1$ in order to provide means to vary the output of the magnetic amplifier. This direct current source is energized from the supply line $17-18$ through the power transformer $T-4$ and the rectifier $S-1$. A switch 19 is positioned in series with this supply line. The bias winding $7-8$ and adjustable resistor $R-18$ permits a setting of flux conditions by varying the voltage applied to said winding $7-8$ within the amplifier $M-1$ for the optimum performance of the control winding $5-6$, described hereinafter, of the amplifier and further provides a means for manually adjusting the voltage supply to the precipitator.

The sensing circuit II , which senses current surges in supply line L_1-L_2 distinguishing between normal and abnormal surges in the line comprises a current transformer $T-3$ which is in series with the line L_1-L_2 . The secondary current of the transformer $T-3$ flows through a resistor $R-15$ connected across the supply line $13-14$ of the transformer. An adjustable resistor $R-17$ is positioned in parallel with the resistor $R-15$, providing a means for setting the voltage to be applied to the primary of the step-up or amplifying input transformer $T-2$. $T-2$ steps up the voltage which is then passed through rectifier $S-6$ to resistor $R-6$. The D.C. voltage across $R-6$ will charge condenser $C-5$ connected in parallel with $R-6$, through the resistor $R-5$.

Under normal operating conditions, a very low voltage appears across resistor $R-5$ and, therefore, no current flows through resistor $R-4$ which has an appreciably smaller resistance than resistor $R-5$ and which is connected in series with cold cathode tube $V-3$, the tube $V-3$ and resistor $R-4$ being connected in parallel with the resistor $R-5$. However, when a current surge takes place in line L_1-L_2 , this surge is transmitted through transformers $T-3$, $T-2$ and rectifier $S-6$, showing up across $R-5$, since the condenser $C-5$ does not have sufficient time to charge up, the time constant between $C-5$ and $R-6$ being so preselected as to permit this. When this surge is reflected across $R-5$, it is of sufficient magnitude to cause the tube $V-3$, which can be of the cold cathode type, to conduct and accordingly voltage appears across the resistor $R-4$, which, as aforementioned, has a lesser resistance than $R-5$ and is in series with the glow tube $V-3$.

Through this sensing circuit II , it is to be noted, current surges in line L_1-L_2 , sensed by the current transformer $T-3$ are translated into voltage surges across the resistor $R-4$, the length of the voltage surges being governed by the constants $R-5$, $R-6$, and $C-5$. It is to be noted further that in the place of the full wave rectifier $S-6$ which transmits surges on both positive and negative portions of the supply in line L_1-L_2 to the resistor $R-6$ (Figure 1), a half wave rectifier $S-7$, as disclosed in Figure 2, can be used in the sensing circuit II whereby only the positive or negative rectified surges can be applied to the resistor $R-6$.

Broadly, the control circuit III connects the sensing circuit II with the amplifying circuit I by linking the control winding $5-6$ of the amplifying circuit I with the resistor $R-4$ of the sensing circuit II .

The control circuit III , which energizes and controls the control winding $5-6$ of the amplifying circuit I , comprises a secondary voltage supply circuit including a supply line $15-16$ across which is connected the primary of the power transformer $T-1$. A switch 32 is positioned in series with the supply line. A direct current voltage is obtained across the lines $c-d$ through the secondary winding of transformer $T-1$ and rectifiers $S-2$ and $S-3$. This voltage is passed through a filter section comprising the series connected resistor $R-12$ and the condenser $C-1$, which condenser is positioned across the line $c-d$. The voltage is then applied to a voltage divider circuit also

positioned across the line $c-d$ and comprising resistors $R-8$, $P-1$, $R-9$, and $R-16$.

Voltage $g-d$, shunted by filtering condenser $C-3$ is applied to condenser $C-6$ through resistor $R-7$ and adjustable resistor $P-3$. The series connected resistors $R-7$ and $P-3$ provide a comparatively long time constant causing the voltage across condenser $C-6$ to build up gradually. The adjustable resistor $P-3$ permits a varying of this time constant if so desired. The gradual build-up of voltage appearing across condenser $C-6$ is applied between the grid 42 and cathode 50 circuit of tube $V-1$ through resistors $R-3$, $R-10$ and $P-2$. As the voltage increases across $C-6$, the grid 42 of vacuum tube $V-1$ becomes more positive with respect to cathode 50 , permitting more current to flow through the tube $V-1$ and consequently winding $5-6$ of $M-1$. Paralleling the condenser $C-6$ is a circuit comprising a condenser $C-4$, shunted by resistor $R-1$, both $C-4$ and $R-1$ being in series with the electronic tube $V-2$. The grid-cathode circuit $38-40$ of tube $V-2$ is connected across the resistor $R-4$ of the surge sensing circuit II . As a result, each time there is a surge across $R-4$, the tube $V-2$ is caused to conduct and accordingly, there is a resulting decrease of voltage across condenser $C-6$, the condenser $C-4$ and resistor $R-1$ limiting the voltage reduction across $C-6$ per surge. It is to be noted that further adjustment of the voltage reduction across $C-6$ per surge can be obtained by setting the voltage $h-d$ applied to cathode 40 of tube $V-2$ by varying resistor $R-16$. Although $V-2$ is disclosed as a triode tube, it is to be understood that other type vacuum tube such as a tetrode or pentode tube can be used.

The voltage across the condenser $C-6$ functions in accordance with the surge across the resistor $R-4$ of the sensing circuit through the grid 38 of the tube $V-2$ parallel with the condenser $C-6$. This voltage is, in turn, applied to the control grid 42 of the high vacuum pentode tube $V-1$. The biasing circuit for the control grid 42 of the tube $V-1$ is also energized from the supply line $15-16$ through the transformer $T-1$ to the lines $e-f$, a D.C. voltage being obtained across the lines $e-f$ through another secondary winding of transformer $T-1$ and rectifiers $S-4$ and $S-5$. This D.C. voltage is passed through a filter section $R-13$ and the condenser $C-2$, which condenser is positioned across the lines $e-f$. The voltage is then applied to a voltage divider circuit comprising the resistors $R-10$, $P-2$, and $R-11$. A resistor $R-3$ positioned in series in the line $e-f$ limits the grid current to the tube $V-1$ should bias voltage be lost.

It is to be noted that this biasing circuit for the control grid 42 also functions in accordance with the surge across the resistor $R-4$ of the sensing circuit through the grid 38 of the tube $V-2$. The anode 48 and grid 44 , and cathode 50 and suppressor grid 46 of the tube $V-1$ are energized across the lines $i-d$ through the resistor $R-14$ in series with this line and the aforementioned control winding $5-6$ of the magnetic amplifier. The polarity of the energy supplied from the lines $i-d$ to the control windings $5-6$ is so arranged that an increasing current results in an increase in the output of magnetic amplifier $M-1$ with which the control windings are associated and accordingly an increase across the winding $3-4$ of the saturable reactor $M-3$. This, in turn, results in an increase of voltage across the primary of the precipitator transformer 30 .

A milliammeter 52 is provided in the cathode line of the tube $V-2$ in order to indicate the number of surges that take place and a voltmeter 54 is provided across the resistor $M-4$ in order to show the operating range of the saturable reactor $M-3$.

It is to be understood that in place of the tube $V-1$, which is disclosed as being a pentode tube, other types of vacuum tubes such as a triode or tetrode tube can be used. It is further to be understood that for the rectifiers throughout the circuit, various types of rectifiers can

be used, such as selenium, mechanical or vacuum type.

In operation, voltage is applied to the precipitator discharge electrode 22 through the precipitator step-up transformer 30 and rectifier 24 from a supply circuit through main supply line L₁—L₂. In an advantageous embodiment of the invention, a 440 volt, 60 cycle voltage can be applied to the line L₁—L₂. However, it is to be understood that various voltages can be used for various precipitator conditions and various resistances, rectifiers and tubes can be used in the disclosed circuit.

If the precipitator is running smoothly and not sparking, there is a steady current flowing through current transformer T-3 of the sensing circuit II, a steady voltage on the condenser C-5 of the sensing circuit II and no current through resistance R-4 of the sensing circuit II.

At the same time, the current through control winding 5—6 of the amplifying circuit I slowly increases as a result of the energization of the control circuit III from the supply line 15—16. This is caused by a gradual rise in voltage across the condenser C-6 of the control circuit III, which, in turn, causes the tube V-1 of the control circuit III to gradually increase in conduction. Since the tube V-1 is in series with the control winding 5—6 of the amplifier circuit I, there is an increase of current through winding 5—6. This causes an increase of current through the direct current winding 3—4 of the saturable reactor M-3. As the voltage to the precipitator rises, it will reach a value, dependent upon the dust condition of the gas flow, to cause sparking or flashover.

When this happens, there is a current surge in the supply line L₁—L₃ which is reflected across current transformer T-3, amplified through input transformer T-2 of the sensing circuit II, and rectified by rectifier S-6. The constants of the sensing circuit II are adjusted so that the difference in voltage between resistor R-6 and condenser C-5, which does not have time to charge up as a result of the surge, is of sufficient magnitude to cause the glow tube V-3 to conduct with a resultant surge appearing across the resistor R-4 of the sensing circuit II. The time length of this surge depends upon the time length of the surge in the main supply line, and its magnitude is in excess of a predetermined value as selected through choice of resistors and adjustment of the resistor R-17 in the sensing circuit II.

Since the grid circuit of the triode tube V-2 in the control circuit III is connected across the resistor R-4 of the sensing circuit II, each surge in this resistor causes the tube V-2 to conduct and accordingly there is a resultant decrease in the voltage across condenser C-6 of the control circuit II.

As was aforescribed, the increase in voltage across condenser C-6 effects an increase of voltage in main supply line L₁—L₂ through tube V-1, magnetic amplifier M-1 and saturable reactor M-3. Accordingly, a decrease in voltage across condenser C-6 will effect a decrease in the voltage across the main supply line. This voltage will decrease until the sparking fails to create a surge in R-4. The voltage then starts to rise again as the condenser C-6 commences to charge upwardly again, the charging of the condenser C-6 being gradual as a result of the long time constant established through the variable series resistors in the control circuit II.

It is to be noted that in certain instances, the amplifying circuit I need not be included as part of the overall circuit, the control circuit being connected directly to the reactor M-3, and it is further to be noted that the saturable reactor M-3 and magnetic amplifier M-1 can be used in conjunction with the sensing circuit without the use of the control circuit, whereby manual regulation can be obtained through the amplifier, the control windings 5—6 of the amplifier being connected to S-6 of the sensing circuit in order to obtain an automatically stabilized manual regulator.

The invention claimed is:

1. A voltage regulating apparatus for an electric load device comprising a main supply line for said load device; a saturable reactor having a main winding and a direct current winding, said main winding being connected in series with said supply line; a magnetic amplifier having a bias winding and an adjustable resistance means associated therewith and being connected to said direct current winding to control flux conditions within said saturable reactor; a sensing means operatively connected with said supply line for obtaining discrete current-responses to current surges in said circuit created by raised voltages across said load device; and a control means connecting said sensing means and said magnetic amplifier for causing said voltage in said supply line to gradually rise through said amplifier and said reactor over a preset voltage range and to drop instantaneously a preselected amount in accordance with sensed current responses translated to said control means by said sensing means.
2. A voltage regulating apparatus for an electric load device comprising a main supply line for said load device; a variable induction means positioned in said supply line; a current transformer positioned in said line; an input transformer having a primary winding connected across said current transformer and a secondary winding; a rectifier connected to said secondary winding; a first resistance unit and a condenser connected in parallel across said rectifier; a second higher resistance unit connected in series between said first resistance unit and said condenser; a third resistance unit of lower resistance than said second resistance unit connected in series with a vacuum glow tube across said second resistance unit, whereby surges detected by said current transformer cause said glow tube to conduct, thereby causing surges of predetermined magnitude to appear across said third resistance unit; and a control means connecting said third resistance unit and said induction means for causing the voltage in said supply line to gradually rise through said induction means over a preset voltage range and to drop instantaneously a preselected amount in accordance with surges appearing in said third resistance unit.
3. The circuit of claim 2 and an adjustable resistance unit connected across said primary winding to thereby vary the magnitude of the surges to which the third resistance unit responds.
4. A voltage regulating apparatus for an electric load device comprising a main supply line for said load device; a variable induction means positioned in said main supply line; a sensing means positioned in said supply line for developing discrete current responses to current surges detected in said line created by raised voltages across said load device; a second supply line, said surges being connected to said variable induction means; a vacuum tube positioned in said second supply line, and a variable preset control means connecting said tube and said sensing means for causing said tube to increase in current conductivity when no surges are detected by said sensing means thereby causing the voltage in said main supply line to gradually rise through said induction means over a preset voltage range and for causing said tube to drop instantaneously a preselected amount in current conductivity when surges are detected by said sensing means thereby causing the voltage across said means supply line to drop instantaneously a preselected amount.
5. The apparatus of claim 4 wherein said variable control means comprises a condenser positioned in a circuit across said second supply line adapted to control the conductance of said vacuum tube; an adjustable resistance unit positioned in said circuit providing a long time constant for said condenser whereby the voltage builds up in said condenser gradually at a prefixed rate and the current conductivity of said vacuum tube in said second supply line accordingly increases at a prefixed

rate; and a second vacuum tube paralleling said condenser, the grid of said second vacuum tube being connected to said sensing means whereby surges detected by said sensing means causes said vacuum tube to operate instantaneously thereby resulting in an instantaneous voltage drop across said condenser and a current decrease across said first vacuum tube.

6. A sensing device for sensing current surges in a supply line of predetermined magnitude comprising a current transformer positioned in said line; an input transformer having a primary winding connected across said current transformer and a secondary winding; a rectifier connected to said second secondary winding; a first resistance unit and a condenser connected in parallel across said rectifier; a second higher resistance unit connected in series between said first resistance unit and said condenser; a third resistance unit of lower resistance than said second resistance unit connected in series with a vacuum glow tube across said second resistance unit, whereby surges detected by said current transformer cause said glow tube to conduct causing surges of predetermined magnitude to appear across said third resistance unit.

7. The circuit of claim 6 including an adjustable resistance unit connected across said primary winding to vary the magnitude of surges to which the third resistance unit responds.

8. A current control circuit for a supply line adapted to increase current in said line at a preselected rate and to drop said current instantaneously in accordance with sensed surges imposed on said line comprising: a first vacuum tube positioned in said line; biasing means for said first vacuum tube; a condenser positioned across said line for controlling said biasing means; an adjustable resistance unit connected in series with said condenser for providing a long time constant for said condenser so that the voltage across said condenser builds up gradually at a prefixed rate to increase the current conductivity of said vacuum tube in said supply line at a prefixed rate and accordingly the current output of said line; and a second vacuum tube paralleling said condenser and adapted to be fired by said sensed surges for causing an instantaneous voltage drop across said condenser and a decrease of current through said first vacuum tube and said line.

9. A voltage regulating apparatus for an electric load device comprising: variable induction means having a main winding and a direct current winding; a supply line for said load and connected in series with said main winding; a magnetic amplifier connected to the direct current winding and having control windings adapted so that an increasing current therein results in an increase in current through the direct current winding of said variable induction means and hence the main supply line; a sensing means for developing discrete direct current responses to current surges in the supply line, said surges being created by raised voltages across said load device; said sensing means comprising a main circuit including first and second resistors and a capacitor so arranged that the direct current voltage across said first resistor will charge the capacitor through said second resistor, and a bypass circuit including a resistance unit in series with a cold cathode glow tube connected across said second resistor and normally carrying no current except as current surges transmitted to the main circuit cause said glow tube to conduct thereby causing corresponding voltage drops across said bypass resistance unit; and control means connected to the control windings of the magnetic amplifier and comprising a secondary voltage supply circuit including a vacuum tube circuit, said secondary supply circuit causing the voltage in the main supply line to rise gradually through the control windings and the variable induction means over a preset voltage range, and said vacuum tube circuit causing the voltage in the main supply line to drop instantane-

ously a preselected amount in response to voltage drops across said bypass resistance unit.

10. The apparatus of claim 9 wherein the grid of a vacuum tube of said vacuum tube circuit is responsive to voltage drops across the bypass resistance unit of said sensing means whereby said vacuum tube circuit causes the voltage in the main supply line to drop instantaneously a preselected amount in response to surges detected by the sensing means.

11. A voltage regulating apparatus for an electric load device comprising a main supply line for said load device; a saturable reactor having a main winding in series with said supply line and a direct current winding connected to a control means; a sensing means positioned in said supply line for obtaining discrete current responses to current surges in said line created by raised voltages across said load device; and said control means connected to said sensing means and said saturable reactor, said control means being connected to said direct winding of said saturable reactor through a magnetic amplifier and causing said voltage in said supply line to gradually rise through said induction means over a preset voltage range and to drop instantaneously a preselected amount responsive to said sensed current responses translated to said control means by said sensing means.

12. An electrical precipitator for removing dust and foreign particles from a gas comprising a discharge electrode for charging said particles, a collecting electrode for collecting said charged particles, an electrical energy source, a saturable reactor having a controlled winding for operatively connecting said discharge electrode and said source and a control winding for controlling said controlled winding, means connected with said control winding actuating the latter so that said controlled winding raises the voltage level of electrical energy supplied to said discharge electrode gradually whereby surges of current to the discharge electrode develop when a voltage level is reached at which sparking between said electrodes occurs, means developing a response to said surges, and means operative by a predetermined response for operating said control winding actuating means to cause said controlled winding to lower the voltage level of energy supplied to said discharge electrode instantaneously.

13. An electrical precipitator for removing dust and foreign particles from a gas comprising a discharge electrode for charging said particles, a collecting electrode for collecting said particles, an electrical energy supply source, a first variable induction means including control means connecting said source and said electrodes for gradually raising the voltage level of the electrical energy supplied to said electrodes from a predetermined level to a level at which sparking between said electrodes occurs, and means responsive to a predetermined magnitude of sparking actuating said control means to reduce said voltage instantly to said predetermined level.

14. An electrical precipitator for removing dust and foreign particles from a gas comprising a discharge electrode for charging said particles, a collecting electrode for collecting said particles, an electrical energy source, variable induction means including control means connecting said source and said electrodes and normally operable for raising the voltage level of the electrical energy supplied to said electrodes from a lower predetermined level at a predetermined rate to a substantially higher level where sparking tends to jump between said electrodes, and means operative in response to sparking of a predetermined magnitude operating said control means to instantaneously lower said voltage to said predetermined level.

15. In an electrical precipitator wherein one electrode charges the dust and foreign particles of a gas with electrical energy supplied from a supply source and another electrode collects said charged particles to remove the particles from the gas, a control for automatically selecting an optimum voltage range for the electrical energy

supplied to said electrodes for any gas-particle condition comprising variable induction means and including control means for gradually raising the voltage level from a lower level to an upper limit, said upper limit manifesting itself by current surges from said source due to 5 sparking between said electrodes, and means operatively connected to said variable induction means and said control means responsive to said surges of a predetermined magnitude for instantaneously lowering said voltage to said lower level.

16. An electrical precipitator for removing dust and foreign particles from a gas comprising a discharge electrode for charging said particles, a collecting electrode for collecting said particles, an electrical energy source, a saturable reactor having a main winding forming a 15 circuit for operatively connecting said discharge electrode and said source and a direct current winding, a magnetic amplifier having a bias winding and an adjustable resistance means associated therewith and being connected to said direct current winding to control flux conditions within said saturable reactor, sensing means operatively connected with said source for obtaining discrete responses to current surges in said circuit, said surges being 20

created by sparking between said electrodes due to the raised voltages across said electrodes and control means connecting said sensing means and said magnetic amplifier for causing the voltage supplied to said discharge electrode to gradually raise through said amplifier and reactor within a preset voltage range and to drop instantaneously in accordance with sensed current responses translated to said control means by said sensing means.
